CLAIM

The ornamental design for a pet bowl holder, as shown and described.

DESCRIPTION

FIG. 1 shows a perspective view of the pet bowl holder.

FIG. 2 shows a front view of the pet bowl holder.

FIG. 3 shows a rear view of the pet bowl holder.

FIG. 4 shows a side view of the pet bowl holder.

FIG. 5 shows an opposing side view of the pet bowl holder.

FIG. 6 shows an underside view of the pet bowl holder; and,

FIG. 7 shows an overhead view of the pet bowl holder.

The broken lines shown represent unclaimed features of the pet bowl holder and form no part of the claimed design.
